UNITED STATES PATENT OFFICE

142,443

DESIGN FOR A LIGHTER FOR CIGARS, CIGARETTES, AND THE LIKE

John N. Robins, Chicago, Ill.

Application May 16, 1945, Serial No. 119,578

Term of patent 7 years

(Cl. D48—27)

To all whom it may concern:

Be it known that I, John N. Robins, a citizen of the United States, residing at Chicago, in the county of Cook and State of Illinois, have invented a new, original, and ornamental Design for a Lighter for Cigars, Cigarettes, and the like, of which the following is a specification, reference being had to the accompanying drawing, forming part thereof.

Fig. 1 is a top plan view of a lighter for cigars, cigarettes, and the like, showing my new design;

Fig. 2 is a side elevational view thereof.

Fig. 3 is a bottom view thereof;

Fig. 4 is an end elevational view thereof, looking in the direction of the arrow 4 in Fig. 2, and

Fig. 5 is an end elevational view thereof, looking in the direction of the arrow 5 in Fig. 2.

I claim:

The ornamental design for a lighter for cigars, cigarettes, and the like, as shown.

JOHN N. ROBINS.
